PLANT LABELING DEVICE

George W. Patten, Minneapolis, Minn.

Application June 9, 1939, Serial No. 278,269

2 Claims. (Cl. 40—19)

My invention relates to a plant labeling device and has for its object to provide a cheap and simple and efficient label carrying member adapted to be held in the ground, either outside or in greenhouses, adjacent plants or rows of plants to name such specific plant or plants.

It is an object of my invention to provide a labeling device which contains a chamber with transparent walls in which is a slip having written, typed, or printed thereon the name of a specific plant, together with any other data which may be desirable to associate with the name.

To this end it is a principal object of my invention to provide a section of ordinary glass tube normally open at each end, to close the ends of the tubing with suitable closure members which may be of rubber, cork, or the like, but preferably will be of rubber, to perforate centrally one of said closures and form a central inner seat on the other closure, and to force through the perforated closure a stem member of a diameter slightly larger than the perforation, so that the end thereof will engage the central seat in the other closure member, thus providing a central reinforcing member for the entire length of tubing. The label will be coiled inside the glass tube with the writing thereon turned outwardly surrounding and being adjustable in position by the stem before its end is seated in the central seating depression of the unperforated closure.

I am aware that it has been proposed to display plant labels within a glass tube, usually in the form of a test tube having a sealed glass end. All forms of such arrangement, of which I have knowledge, are too expensive to manufacture and impractical to apply. So far as I know, the organization of elements by which I accomplish the objects above stated is not only novel, but is the first such organization to produce a practical label containing tube structure which is strong enough to resist strains, which can be made cheaply enough to make it available for use, and which is provided with a removable ground engaging stem, which at the same time is positioned throughout the extent of the inner portion of the tube and forms a sort of reinforcing bridge for the tube and holds it strongly enough on the stem to prevent breakage from strains.

The full objects and advantages of my invention will appear in connection with the detailed description thereof and the novel features which produce the aforesaid desirable results will be particularly pointed out in the claims.

In the drawing illustrating an application of my invention in one form:

Fig. 1 shows an elevation view of the labeling device as the same would appear when held in the ground.

Fig. 2 is a view of the device similar to Fig. 1 with the label and label holding members in longitudinal section.

Fig. 3 is a sectional view of the centrally perforated closure member.

Fig. 4 is a sectional view of the closure member having a central seat.

Fig. 5 is a plan view of a suitable label for insertion within the tube.

Fig. 6 is a view similar to Fig. 2 showing the thinner tube which may be employed when made of Cellophane or the like.

As shown, a section of glass tubing 10 is provided. This may be formed from ordinary inexpensive glass tubing cut to suitable length, and while I prefer ordinary glass tubing as above noted, since that may be obtained at a reasonable cost, I am not limiting myself to glass tubing, as any transparent substance, such as Cellophane or other tubing made from plastic materials, is within the scope of my invention.

A closure member 11 is provided for one end as at 12, of the tube 10. This closure member will preferably be of rubber, although I am not limiting myself to any particular type of material. It will be of a size so that when forced into the open end 12 of the tube 10, it will effect a substantially permanent seal of that end. The closure member 11 is provided with a depression or seat 13, as clearly shown in Fig. 11.

For the other end of the tube 10 a closure member 14 of the general character shown in Fig. 3 is provided. Preferably, this closure member will have a large cavity or bore 15 extending partly through its body along the center line thereof and a somewhat smaller bore 16 which goes to the outside. A stem 17 has a somewhat conical or pointed end 18 which is adapted to be forced through the bore 16 when the closure 14 is in position on the end of the tube 10, as in Fig. 2, and this conical end 18 will be placed within the seat 13 of the closure 11, as shown in Fig. 2. In this position the stem 17 will have a portion 19 extending through the center of tube 10 which is effectively anchored in the closures 11 and 14 and which thus operates as a stiffening and reinforcing member for the structure, and which, when the stem 17 is thrust in the ground as in Fig. 1, holds the tube throughout its length. This will hold the tube rigidly in alignment with the

stem 17 and will prevent oscillation of the tube upon the closure 14, which might set up strains which would either break the end of the tube, as at 20, or would cause the closure 14 to be partially or wholly withdrawn therefrom.

Labels 21 may have displayed thereon by writing, typing, or printing, the names of plants, dates when seed to produce the plants is planted, where obtained, or other matter carrying desired information. This label 21 will be of a length and breadth such that when it is rolled, it will fit into the tube 10 with its written, typed or printed matter exposed outwardly against the inner surface of tube 10 to be easily read.

15 It is desirable to provide a lip 22 on closure 14 to insure that the closure will not be forced into the tube 10 when the stem 17 is being pushed through it into position, although I do not wish to limit myself for all purposes to a closure 14 having a lip such as lip 22.

20 While glass tubing is satisfactory for the outer transparent enclosing member 10, under certain conditions it may be advantageous to employ a tube of composition material, as for example, 25 Cellophane. Such a tube is shown at 25 in Fig. 6, and except for the change of material, will co-operate with the other elements in the same manner as the glass tubing.

25 The advantages of my invention have been given quite fully in connection with the detailed description thereof. The primary advantage is that a label holding member is provided which is adapted to be inserted in the ground, either outdoors or in greenhouses, and in beds, pots and 30 the like, or adjacent single plants or at the ends

of rows of plants, which will contain names and other data providing desired information, which is sufficiently inexpensive so that it is practically available for general use, and which is so held by the relation of the stem to the closures that 5 the label holding tubular member cannot be displaced on the stem and under all practical conditions cannot be broken.

I claim:

1. A label-holding device for plants comprising 10 a transparent open-ended tube for receiving a label and exposing the matter thereon to view, closures for the ends of the tube, one of said closures being removable to permit insertion of the label, and a stem passing through one of said 15 closures and having its end entering the body of the other closure to hold the tube in rigid unchangeable relation to the stem, said stem adapted to be thrust into the ground to hold the label positioned for convenient inspection. 20

2. A label-holding device for plants comprising a transparent open-ended tube for receiving a label and exposing the matter thereon to view, a fixed closure at one end of the tube provided with a central seat, a removable closure for the 25 other end of the tube provided with a central bore, and a metallic stem extending through the bore of said removable closure and having a conical end engageable in the seat of the fixed closure to hold the tube in rigid unchangeable relation to the stem, said stem adapted to be thrust into the ground to hold the label positioned for 30 convenient inspection.
